UNITED STATES PATENT OFFICE.

JOSEPH C. GASKILL, OF OSWEGO, NEW YORK, ASSIGNOR TO AMES IRON WORKS, OF OSWEGO, NEW YORK, A CORPORATION OF NEW YORK.

STEAM-ENGINE.

1,283,145.

Specification of Letters Patent. Patented Oct. 29, 1918.

Application filed August 19, 1915. Serial No. 46,308.

To all whom it may concern:

Be it known that I, Joseph C. GASKILL, a citizen of the United States, residing at Oswego, in the county of Oswego and State 5 of New York, have invented a certain new and useful Steam-Engine, of which the following is a specification.

This invention relates to steam engines and has special reference to engines having 10 a cylinder provided with valve controlled inlets at its ends and piston controlled central outlet ports, these engines being commonly designated as of the "una-flow" type.

In engines of this description it is frequent 15 that the engines are used either as condensing or non-condensing and it also frequently happens that, through some accident or disarrangement of the parts, the vacuum which should be produced in a condensing engine is broken so that the engine virtually becomes a non-condensing engine. This results in an undue compression of the steam, remaining in the cylinder after 20 exhaust, between the piston and the cylinder head.

One principal object of the invention is to overcome this difficulty by providing means for automatically increasing the compression space whenever the vacuum is broken 30 or reduced.

A second important object of the invention is to provide improved means for accomplishing this object in such manner as to dispense with all auxiliary exhaust valves 35 and valve gear.

A third object of the invention is to provide an improved and simplified automatic means controllable by the degree of vacuum in the exhaust pipe or space of the engine for 40 opening and closing communication between the interior of a cylinder and an auxiliary compression chamber.

With the above and other objects in view the invention consists in general of certain 45 novel details of construction and combinations of parts hereinafter fully described, illustrated in the accompanying drawings and specifically claimed.

In the accompanying drawings like characters of reference indicate like parts in the several views, and

Figure 1 is a longitudinal vertical section through one end of an engine cylinder showing the improvements of the present invention applied thereto.

Fig. 2 is a section on the line 2—2 of Fig. 1, certain of the parts being shown, in elevation.

In the embodiment of the invention herein illustrated there is disclosed an engine cylinder 10 one end only of which is shown, the other end being similar in construction and being omitted for the sake of showing the device on a larger scale.

Forming part of this cylinder, at each end 65 is a head 11 wherein is provided an intake passage 12 controlled by a valve 13 and opening into the cylinder through a port 14. Intermediate the ends of the cylinder are provided exhaust ports 15 which open into 70 an exhaust chamber 16 surrounding the center of the cylinder 10 and having an exhaust fitting 17 formed in connection therewith so that the exhaust chamber may be connected to any suitable condenser (not shown). The 75 piston 17' is provided with the usual piston rod 18 and the stroke of the engine and dimensions of the piston are such that when the piston is at one end of the cylinder the exhaust ports 15 will be open to the other 80 end of the cylinder 10.

In each head 11 is provided a valve cage seat 19 located in any suitable position and having communication with a supplemental compression chamber 20, the valve cage seat 85 also communicating with the interior of the cylinder body by means of a passage 21. In this seat is located a valve cage 22 which is secured in position by any suitable means, as by bolts 23. This cage is provided on the 90 end adjacent the passage 21 with a valve seat whereon is normally seated a valve 24 controlling the passage of steam between the interior of the cylinder to the chamber 20 and the valve is provided with a stem 25 95 having a piston 26 on its lower end which is mounted in a cylinder 27 fixed to the valve cage in any suitable manner, as by bolts 28. Within the cylinder 27 adjacent its head is a follower 29 the position of which may be 100 regulated by an adjusting bolt 30 and between this follower and the piston 26 is a compression spring 31 whose normal tendency is to lift the piston and move the valve 24 off its seat, thereby opening communication between the cylinder 10 and chamber 20. In order to hold the valve 24 on its seat when the engine is operating as a condensing engine the chamber 16 is connected to the cylinder 27 by a pipe 32 so that when a 105

vacuum is established in the chamber 16 by the condensation of the steam a similar vacuum will be formed in the cylinder 27 and the piston 26 drawn downward against the spring 31 thereby cutting off communication between the cylinder 10 and chamber 20. So long as the proper degree of vacuum is maintained the valve will remain closed. If, however, the vacuum be broken or reduced beyond a point determined by the adjustment of the bolt 30, the valve 24 will open and the residue steam will not be confined in space between piston 17', cylinder head 11, and valve 24 thus unduly compressing this residue steam but will be allowed to enter the supplemental chamber 20 thereby preventing excessive compression in the cylinder 10 as would be present were this steam to be compressed in the cylinder 10 between the piston 17', cylinder head 11, and valve 24.

The space above piston 26 is placed in communication with the atmosphere by a vent 33, here represented as formed in the wall of the valve-cage 22.

What is claimed is:

1. A steam engine having an auxiliary compression chamber and a steam cylinder communicating with the chamber, said steam cylinder being provided with an exhaust, and means operable by the pressure in the exhaust through a communicating connection from the exhaust, to govern the communication between said steam cylinder and said compression chamber before excessive compression occurs in the steam cylinder.

2. A steam engine having an auxiliary compression chamber and a steam cylinder communicating therewith, said steam cylinder being provided with an exhaust, a valved means controlling the communication between the cylinder and chamber, a communicating connection between the exhaust and the valved means, said valved means controlled by the pressure in the exhaust to govern the opening and closing of the valved means, before excessive compression occurs in the steam cylinder.

3. A steam engine having an auxiliary compression chamber and a steam cylinder communicating therewith, said steam cylinder being provided with an exhaust, a valve controlling the communication between the cylinder and chamber and provided with a stem, a valve piston on said stem, a valve cylinder wherein the valve piston moves, a spring in the valve cylinder urging said valve to open, and a pipe connecting the exhaust and valve cylinder.

4. A steam engine having an auxiliary compression chamber and a steam cylinder communicating therewith, said steam cylinder being provided with an exhaust, a valve controlling the communication between the

cylinder and chamber and provided with a stem, a valve piston on said stem, a valve cylinder wherein the valve piston moves, a spring in the valve cylinder urging said valve to open, means to vary the tension of said spring and a pipe connecting the exhaust and valve cylinder.

5. The combination with a steam engine cylinder, of a clearance pocket communicating therewith, a valve controlling the outlet from said cylinder to said pocket, means to hold the valve open when the engine is running non-condensing, and means controlled by vacuum in the exhaust pipe of the engine to close said valve when the engine is running condensing.

6. The combination with a steam engine cylinder, of a closed clearance chamber communicating therewith, a valve controlling the communication between said cylinder and chamber, and means controlled by vacuum in the exhaust pipe to close said valve when vacuum exists and open said valve when the vacuum fails.

7. The combination with a steam engine cylinder, of a closed clearance chamber communicating therewith, a valve controlling said communication, a small cylinder, a piston therein connected to the valve, and a pipe connecting one end of the small cylinder and the exhaust pipe of the engine, the other end of the small cylinder having a vent.

8. The combination with a steam engine cylinder, of a closed clearance chamber communicating therewith, a valve controlling said communication, a small cylinder, a piston therein connected to the valve, a pipe connecting one end of the small cylinder and the exhaust pipe of the engine, the other end of the small cylinder having a vent, and a spring coöperating with the piston and tending to open the valve.

9. The combination with a steam engine cylinder, of a closed clearance chamber communicating therewith, a valve controlling said communication and opening inwardly with respect to the cylinder, a piston connected to said valve and exposed on one side to atmospheric pressure and on the opposite side to the exhaust pressure of the engine, whereby, when vacuum exists, the atmospheric pressure will shift the piston and close the valve, and means tending to open the valve.

10. The combination with a steam engine cylinder, of a closed clearance chamber communicating therewith, a valve controlling the communication between said cylinder and chamber, a piston connected to the valve, means to shift said piston and hold the valve open when the engine is running non-condensing, and a connection from one side of the piston to the exhaust passage of the engine, adapted to shift said piston and

close the valve when vacuum exists in the exhaust passage.

11. The combination with a steam engine cylinder, of a clearance pocket communicating therewith, a valve controlling said communication and arranged to open inwardly to the cylinder, means to hold said valve open while the engine is running non-condensing, and means actuated by vacuum in the exhaust passage of the engine to hold said valve closed while the engine is running condensing.

12. The combination with a steam engine cylinder, of a closed clearance chamber communicating therewith, a valve controlling communication with said chamber, and means governed by variations of pressure in the exhaust pipe of the engine for holding said valve closed when the engine is running condensing and for holding said valve open when it is running non-condensing.

13. A steam engine having an auxiliary compression chamber and a steam cylinder communicating therewith, said steam cylinder being provided with an exhaust, a valve controlling the communication between the cylinder and chamber and provided with a stem, a valve-operating piston on said stem, a cylinder wherein the piston moves, a spring in the cylinder urging said valve to

open, and a pipe connecting the exhaust and said cylinder.

14. A steam engine having an auxiliary compression chamber and a steam cylinder communicating therewith, said steam cylinder being provided with an exhaust, a valve controlling the communication between the cylinder and chamber and provided with a stem, a valve-operating piston on said stem, a cylinder wherein the piston moves, a spring in the cylinder urging said valve to open, means to vary the tension of said spring, and a pipe connecting the exhaust and said cylinder.

15. The combination with a steam engine cylinder, of a closed clearance chamber communicating therewith, a valve controlling said communication, a small cylinder, a piston therein connected to the valve, and a pipe connecting one end of the small cylinder and the exhaust pipe of the engine, the other end of the small cylinder having a vent, and a spring pressing against the piston and tending to open the valve.

In testimony whereof, I affix my signature, in the presence of two witnesses.

JOSEPH C. GASKILL.
